A. L. ASTE.

POWDER BOX.

APPLICATION FILED MAY 10, 1919.

Patented Nov. 2, 1920.

INVENTOR
Anthony L. Aste,

BY *C.P. Goepel.*

ATTORNEY

UNITED STATES PATENT OFFICE.

ANTHONY L. ASTE, OF BROOKLYN, NEW YORK.

POWDER-BOX.

1,357,306.

Specification of Letters Patent. Patented Nov. 2, 1920.

Application filed May 10, 1919. Serial No. 296,203.

To all whom it may concern:

Be it known that I, ANTHONY L. ASTE, a citizen of the United States, and a resident of the borough of Brooklyn, county of 5 Kings, city and State of New York, have invented certain new and useful Improvements in Powder-Boxes, of which the following is a specification.

This invention relates to powder boxes 10 and has for its primary object to provide improved means for assembling in compact relation with the body of the box, a holder for a pad, cloth or other applicator.

More particularly, the present invention 15 contemplates the provision of a box or receptacle such as is commonly used for talcum powders, the body of the box having a false bottom wall provided with a central upwardly projecting portion affording a recess, and a detachable bottom section for the box, frictionally held in assembled relation therewith and adapted to contain the pad or other applicator member which projects from the open side of the bottom section 20 and into said recess.

It is a further general object of my invention to provide a powder box or container having a detachable bottom section which is of such construction that the invention may 30 be readily applied to boxes or containers of various shapes and without greatly increasing the manufacturing cost thereof.

With the above and other objects in view, the invention consists in the improved combination, arrangement and construction of 35 the several parts, as will be hereinafter more fully described, subsequently claimed and illustrated in the accompanying drawing in which similar reference characters 40 designate corresponding parts throughout the several views and wherein—

Figure 1 is a perspective view, partly broken away, of a talcum powder box constructed in accordance with one embodiment 45 of my invention;

Fig. 2 is an enlarged vertical section through the base portion of the box;

Fig. 3 is a detail perspective view of the base section detached from the body of the 50 box;

Fig. 4 is an elevation, partly in section, illustrating a slightly modified construction of the invention and showing the same as applied to another form of box; and

55 Fig. 5 is a detail fragmentary vertical sec-

tion showing another alternative form of the device.

It is customary in establishments devoted to the polishing of shoes to provide the employees with boxes containing talcum powder which is applied to the surfaces of the shoe and briskly rubbed thereover with a cloth in order to enhance the polish or gloss on the shoe surface. It is the primary object and purpose of my present invention to provide the talcum powder box with improved means whereby the polishing cloth or pad may be compactly arranged and carried by the box or container, so that it will not be likely to be misplaced and lost.

In Fig. 1 of the drawing I have illustrated a talcum powder box having a body 5, which may be either of elliptical or circular form in cross section. This body is provided at its upper end with the usual 70 perforated cap 6 and a shiftable disk for opening and closing the perforations in said cap. The wall of the body 5 at its lower end is forced inwardly and upwardly by means of a suitable die whereby a circumferential 75 bead 7 is formed and an annular inwardly extending longitudinal portion 8 in close contact with the body wall of the box. 9 designates the false bottom wall which is thus formed within the lower end of the 80 box body, and the central portion of this wall is upwardly projected as at 10, to thereby produce an exterior recess 11 in said false bottom wall. The detachable base section 12 of the box is reduced in diameter 85 at one of its ends to provide the longitudinally extending flange 13, which is adapted for tight frictional engagement against the inner face of the inturned portion 8 of the body wall of the box. The annular section 90 of the false bottom wall 9, which connects the portion 8 with the upwardly projected portion 10 affords a stop shoulder with which the end of the flange 13 is adapted to contact. Within the detachable bottom 95 section 12 of the box a pad or cloth indicated at 14 is adapted to be arranged. A portion of this cloth projects beyond the open end of the bottom section 12 and is received within the recess 11 of the box bottom. By providing this recess, it is possible to employ a relatively shallow bottom section 12.

In the use of the device, the powder is shaken from the box through the perfora- 110

tions in the cap thereof upon the shoes, and the bottom section 12 is detached from the box body and the cloth or other polishing member removed therefrom. This cloth is 5 then applied to the surfaces of the shoe in the usual manner. It will be apparent, however, that, if desired, the cloth or pad may be permanently secured within the detachable section 12 of the box, especially when 10 the device is intended for other uses than that to which I have above referred.

In Fig. 4 of the drawing I have disclosed a slightly modified construction of the box wherein the false bottom wall 9' is stamped 15 from a separate piece of metal and the lower edge of the body wall of the box is securely clenched and held within the outwardly turned bead 7' on the lower edge of said bottom wall. In all other respects, the construction 20 is identical with that which I have above described. I have, however, shown this modified construction as adapted to a relatively shallow cylindrical box 5', such as is usually employed as a container for 25 toilet powders. In such case, the detachable box bottom might be provided with a pad of chamois or cotton permanently fixed therein, though it is to be understood that in connection with this type of box I might 30 also use the removable cloth or other applicator member.

From the foregoing description considered in connection with the accompanying drawing, the construction of my improved powder box, and its several advantages in practical use, will be clearly and fully understood. The bottom section of the box may be easily and quickly applied and is securely held in connection with the body section by 40 the tight frictional engagement of the flange 13 with the wall 8. The cloth 14, which is housed within this body section, is thus very compactly held and retained by the assembled sections of the box, so that it will not 45 be misplaced or lost, and is always ready for instant use. The two sheet metal sections of the box can be readily formed or stamped by means of suitable dies in an expeditious and inexpensive manner, so that 50 the box may be employed as a container for

talcum powders and the like at a cost which is but slightly in excess of that incident to the use of the present box construction.

In Fig. 5 of the drawing I have illustrated another construction wherein the part 55 8' is not provided with the flange or shoulder 9, but is extended in contact with the body wall of the box to its point of juncture with the false bottom 10'. This part 8' is separately formed and at its edge is turned 60 outwardly and together with the edge of the body wall of the can formed into the bead 7'. The detachable base section 12' is relatively deep and the flange 13' thereof which frictionally engages within the part 8' preferably 65 is relatively short and does not contact with the bottom wall 10'. By this construction, the device is somewhat simplified and a chamber of considerable capacity afforded for the reception of the cloth or pad. 70

While I have herein shown and described several practical forms of my invention, it is nevertheless apparent that the device may also be exemplified in various other alternative constructions, and I accordingly reserve 75 the privilege of adopting all such legitimate changes as may be fairly embodied within the spirit and scope of the invention as claimed.

I claim—

A powder box comprising a box body having a false bottom offset inwardly and in stepped relation relatively to the plane of the lower edge of the box body, the said bottom being stepped from wall to wall of the 85 box body and the lower portion of said bottom being equal substantially to the diameter of the box body, and a powder puff holder of substantially the same diameter as the box body and provided with an upper 90 reduced portion adapted to frictionally engage in said stepped bottom, said powder puff holder providing a true bottom for the box body upon which the latter is adapted to rest.

In testimony that I claim the foregoing as my invention I have signed my name hereunder.

ANTHONY L. ASTE.
